[57] CLAIM

The ornamental design for a stereo speaker assembly for a personal watercraft, as shown and described.

DESCRIPTION

FIG. 1 is a perspective view of a stereo speaker assembly for a personal watercraft showing my new design, the broken line showing of the watercraft is for illustrative purposes only and forms no part of the claimed design;

FIG. 2 is a top plan view with the straps shown in an extended position;

FIG. 3 is a front elevational view, the rear view being a mirror image;

FIG. 4 is a left end elevation view;

FIG. 5 is a right end elevational view; and,

FIG. 6 is a bottom plan view.
